(57) CLAIM

The ornamental design for a shoe as shown and described.

DESCRIPTION

FIG. 1 is a front and right side perspective view of a shoe, showing my new design;

FIG. 2 is a front and left side perspective view thereof;

FIG. 3 is a right side view thereof;

FIG. 4 is a left side view thereof;

FIG. 5 is a front view thereof; and,

FIG. 6 is a top view thereof.

The bottom view is not shown and forms no part of the claimed design. The features shown in broken lines depict portions of the shoe that form no part of the claimed design.
